(57) **CLAIM**

The ornamental design for an image output device, as shown and described.

DESCRIPTION

FIG. 1 is a perspective view of image output device;

FIG. 2 is a top view thereof;

FIG. 3 is a bottom view thereof;

FIG. 4 is a left-side view thereof;

FIG. 5 is a right-side view thereof; and,

FIG. 6 is a front view thereof.

The rear view of image output device contains no ornamental-
ality and is therefore omitted.

The broken lines define the bounds of the claimed design but
do not form part of the claimed design.
